UNITED STATES PATENT OFFICE.

DANIEL E. D. McMURRAY, OF BROOKLYN, NEW YORK.

DESIGN FOR A WATCH-CASE.

SPECIFICATION forming part of Design No. 17,280, dated April 26, 1887.

Application filed February 7, 1887. Serial No. 226,853. Term of patent 7 years.

To all whom it may concern:

Be it known that I, DANIEL E. D. McMURRAY, a citizen of the United States, residing in Brooklyn, in the county of Kings and State of New York, have invented and produced a new and original Design for Watch-Cases, of which the following is a specification, reference being had to the accompanying drawings, forming a part thereof, in which—

10 Figure 1 is a side elevation of my newly-designed case. Fig. 2 is a sectional view on line xx of Fig. 1, and Fig. 3 is a sectional view on line yy of Fig. 1.

15 The leading feature of my design consists in a general octagonal outline when viewed from the side, as illustrated in Fig. 1.

In the drawings, A represents the center of the case, which is octagonal in its general contour, and B B are the case-lids, that are circular 20 in their outer contour. The angles formed by the meeting of the sides of the case-center may

be slightly rabbeted, as indicated, so that although the general effect of the case, when viewed in outline, is octagonal, still the sharp edge of the angles will be seen as being slightly modified, the effect upon the eye being that of an octagonal outline with the angles relieved. Every other one of the side faces of the center A is slightly curved, while the other faces are straight. The effect obtained by viewing the edge of the watch from different points will be seen by inspecting Figs. 2 and 3.

I claim—

The design herein shown and described for a watch-case, the same consisting of a center 35 having an octagonal outline with relieved angles, the several faces being alternately straight and curved transversely.

D. E. D. McMURRAY.
